UNITED STATES PATENT OFFICE.

ANDREW RYCKMAN, OF CHICAGO, ILLINOIS.

CAN OPENER.

Application filed January 22, 1927. Serial No. 162,914.

My invention relates to improvements in can openers, being more particularly concerned with the provision of a can opener suitable for use in hotels, factories, etc. where it is desired to open a great many cans expeditiously and with a minimum effort.

One of the objects of my invention is the provision of such a can opener capable of holding and severing the tops of cans of various sizes with a minimum of physical effort.

Another object of my invention is the provision of such a can opener having means to gauge the height of any can within the usual range of sizes to adjust the cutting element at proper height for said can, and means to move the cutting element into and out of operating position for opening a plurality of cans of the same size without changing said adjustment.

Another object of my invention is the provision of such a can opener having means for holding such a movable cutting element in operating position and means to hold the same in proper position for the insertion of a can.

Other objects and advantages of my invention will appear more fully from the following description and from the accompanying drawings in which similar characters of reference indicate similar parts throughout the several views.

In the drawings Fig. 1 is a side elevational view of my can opener showing a can in position to be opened;

Fig. 2 is a plan view of the same;

Fig. 3 is an elevational cross-sectional view taken on the line 3—3 of Fig. 1;

Fig. 4 is a detail view in partial cross-section of the linkage employed in my can opener;

Fig. 5 is a similar view of a modified form of linkage.

Referring to Figs. 1, 2, and 3, my can opener comprises a supporting frame preferably including a substantially flat base 10 having a plurality of downwardly extending legs 11 and an upwardly extending rearward flange 12 for a purpose further to be explained. The base 10 is preferably constructed of cast iron and may be of any shape or conformation other than that shown in the plan view but the shape shown provides sufficient flat upper surface to accomplish the purposes of the invention without unduly increasing its size and weight.

The base 10 is preferably provided with a slot 13 extending inward from one side of the base and having substantially parallel edges 14 to form a guide. The base 10 is also provided with an aperture 15 of substantially the same length as the slot 13 and having parallel edges 16. The aperture 15 is preferably provided with an enlarged portion 17 at its inner end for the purpose of permitting the insertion of the slider 18 further to be described.

The base 10 is provided with a downwardly extending lug 19 having a bore 20 which is adapted to journal a shaft 21 which is provided with a left-hand threaded portion 22 and the right-hand threaded portion 23. The shaft 21 is preferably provided with a reduced end thereby providing an annular shoulder 24 which serves as a thrust bearing against the lug 19 and the shaft 21 is also provided with a crank 25 having a sleeve 26 which may be keyed or pinned to the shaft 21 as at 27 and which is adapted to rotate the shaft 21 by means of the handle 28. The shaft 21 is provided with a slider 18 having an aperture 30 provided with complementary right-handed threads, and having a pair of horizontally projecting lugs 31 and 32 which are adapted to slide upon the lower surface of the base 10 when the shaft 21 is journaled in the lug 19. The slider 18 is also provided with an upwardly extending lug 33 projecting through the aperture 15 in the base and extending above said base. The lug 33 is provided with a clamping shoe 34 comprising a cast metal member having a substantially flat lower surface, and a pair of diagonally projecting arms 35 and 36 having a side surface 39. The shoe 34 may be fixedly supported upon the lug 33 by a screw bolt 40.

The shaft 21 is also provided at its right-hand threaded portion 23 with a second slider 41 having a similar threaded aperture 42 with complementary right-hand threads, with similar horizontal projecting shoulders to slide on the lower surface of the base 10, an upwardly projecting lug 44 extending through the slot 13 and supporting by the screw bolt 45 the clamping shoe 46. The shoe 46 may be of similar construction to the shoe 34 having diagonally projecting arms 35 and 36 with a serrated side surface 39.

The method of assembly of the foregoing parts is as follows:

The slider 18 may be threaded upon the

shaft 21 and the slider 41 threaded upon the other end of the shaft 21. Both sliders should preferably be somewhere near the inner limit of their range of movement upon the threaded portions 22 and 23 and the slider 18 should be so located that when the upper end of the slider is passed bodily through the aperture 18 the end of the shaft 21 may clear the inner side of the lug 19 for insertion into the journal 20. The crank 25 may then be permanently attached to the shaft 21 and the shoes 34 and 46 fixed to the lugs 33 and 44. It will thus be observed that the shaft is not only supported by the journal 20, but the lower surface of the shoe 46 sliding on the base 10 supports the other end of the shaft 21, while the projecting lugs 43 and 32 upon the sliders cooperate with the opposed surface of the shoes 34 and 46 to retain the sliders within the guides formed by the adjacent edges of the base 10. As the shoes 34 and 46 are provided with the diagonally disposed serrated surfaces 39, it will be obvious that rotation of the crank 25 by means of the handle 28 may cause the shoes 34 and 46 to move toward each other to clamp the base of a can of any of the usual sizes, or to move away from each other to release the same.

In order to reinforce the base 10 it may be provided with a plurality of rearwardly extending reinforcing flanges 47 and a pair of transverse reinforcing flanges 48 along the sides of the slot 13 and aperture 15. The base may also be provided with a plurality of countersunk holes 49 for the insertion of screws to fasten the same to a table or work bench.

The base 10 may support by means of the lug 11 and flange 12 an upright standard 50, which may consist of a substantially rectangular plate of metal, preferably steel having a substantially rectangular slot 51 cut in each edge. The standard 50 may be attached to the base by means of a plurality of screw bolts 52 and it may also be provided with a plurality of countersunk apertures 53 for the purpose of fixing the same to a vertical wall 54 by screws 55 when so desired.

The standard 50 supports for sliding movement a plurality of sliders 56 comprising substantially flat members of angle iron having inwardly turned flanges 57 which are adapted to be received in the grooves 51 to slide therein. The sliders 56 are each provided with a pair of apertures 58 to receive the parallel bolts 59 and 60. The bolts 59 and 60 are turned down at their ends as at 61 to provide annular shoulders 62 against which the sliders 56 may be clamped by the nut 63 to hold the same in fixed relation without binding in the slots 51. The bolt 60 supports for pivotal movement a lever 64 having a downward and rearwardly projecting leg 65, a horizontal leg 66, a vertical bore 67, a goose neck 68, and a pair of horizontal bores 69

and 70 for a purpose further to be described. The leg 65 may be provided with a bore 71 adapted to receive the bolt 60 and a projecting boss 72 at each end providing a journal of substantially the same length as the distance between the shoulders 62.

The journal 67' may be provided with a shaft 73 having a beveled gear 74 keyed or splined thereto and the shaft 73 may be supported within the bore 67 by a collar 75 fixed upon said shaft by a set screw 76. The bevel gear 74 may be provided with the usual annular boss 77 on its lower side and the boss 77 supports by means of the screw bolts 78 and 79, a guide plate 80 which may be of substantially square metal plate having a rectangular groove 81 in its upper surface and a pair of counter-bored apertures to receive the screw bolts 78 and 79 with their heads.

The guide plate 80 is also provided with a central aperture 82 counter-bored within the groove 81 and which is adapted to receive the screw bolt 83 with its countersunk head. The screw bolt 83 is ground to a conical point and in order to support the same firmly in the guide plate 80 and to cover the screw bolts 78 and 79 a washer 85 may be passed over the point 84 and a nut 86 screwed thereon to firmly clamp the screw bolt 83 in the guide plate 80 and to retain the said washer in place.

The guide plate 80 is adapted to receive a substantially rectangular bar 87 in the groove 81 for sliding movement and in order to fix the bar 87 in any adjusted position a set screw 88 may be threaded in the guide plate 80. The bar or cutting arm 87 may be provided at one end with an aperture 89 which is adapted to receive a bolt 90 to clamp the flange 91 of a cutter 92. In order to support the cutter 92 fixedly without pivotal movement I provide a substantially U-shaped stirrup 93 adapted to closely fit the arm 87 on both sides and to receive the bolt 90 through its yoke. By making the cutter flange 91 of substantially the same width as the arm 87 the cutter is adapted to be clamped between the stirrup 93 and the bar 87 by the bolt 90 and is firmly held against the pivotal movement by the upwardly projecting legs of the U-shaped stirrup 93. The cutter 92 is preferably of substantially triangular shape as shown in Fig. 3 with a sharp upwardly sloping cutting edge on each side so that it is adapted to pierce the top of the can by its point and to cut the top of the can by being moved in the direction of either cutting edge, the slope of the cutting edge aiding the cutter in making a slashing cut. The point 84 and cutter 92 are preferably made of the best tool steel so that the piercing and cutting parts may withstand long and continuous service. It will thus be observed that by the means of the set screw 88 and the sliding bar 87 my cutter may be adjusted to sever the top of any ordinary sized can or to cut out

the top as closely to the side walls of the cam as is desirable.

In order to actuate the bevel gear 74 and the cutter 92 I provide a horizontal shaft 94 which may be journaled in the bores 69 and 70 and the shaft 94 supports a second bevel gear 95 which is keyed or splined to move with said shaft. The shaft 94 may be actuated by a crank 96 which has a sleeve 97 keyed or pinned to the shaft 94 and a handle 98. The shaft 94 is retained within its journals by means of the bevel gear 95 which is pinned to the shaft as at 99.

In order to more easily move my cutting mechanism into and out of the operating position, I provide a second lever 100 having a substantially straight lower portion 101 and an upwardly bent handle 102 which may extend over the goose neck 68. The lever 100 has a bore 103 which is adapted to receive the bolt 59 by which the lever is pivotally supported and the horizontal portion 101 is pivotally connected to the leg 66 of the cutter supporting lever by means of a link 104 and a plurality of bolts 105 and 106. The arrangement and shape of the legs 65 and 66 of the lower lever and the portion 101 of the upper lever should preferably be such that when the cutter arm 87 is in horizontal position the centers of the bolts 59, 105 and 106 are in substantial alignment, the links 101 and 104 forming a toggle which substantially locks the levers in position where upward force upon the cutter 92 cannot change the position of this linkage.

In order to limit the downward movement of the lever 100 the link 104 may be provided with substantially U-shaped ends, the yoke 107 providing a limiting stop against which the lever 100 may bear to limit its downward movement. It will thus be observed that when the linkage is in full line position shown in Fig. 4 the toggle cannot be broken by pushing upward upon the handle 98 or other parts connected with the lower lever 64 but by pulling upward upon the handle 102 of the lever 100 the toggle will be broken, the pivot bolt 105 passing upward out of alignment and the link 104 pulling the lever 64 together with its associated mechanism and cutter upward out of contact with the cam. The relative positions of the toggle levers are then shown in the dotted lines of Fig. 4. If desired the stop 107 may be so arranged that the center of the bolt 105 will be slightly below the line of centers of the bolts 59 and 106 thereby setting the toggle past dead center but it is sufficient to have these centers in line so that the toggle is on dead center.

In order to support the sliders 56 in fixed relation upon the standard 50 the bolt 59 may also pivotally support a cam 108 having a surface increasing in radius below the bolt 59 as at 109 and having a projecting bolt

110 for manual actuation. It will thus be observed that if the bolt 110 is pushed downwardly the increasing radius of the cam 108 will cause the cam to bear against the standard 50 and cause the flanges 57 to bind in their grooves as well as to clamp the part of the upright 50 between the cam 108 and the flange 57. The weight of the bolt 110 itself is sufficient to actuate the cam 108 to clamp the sliders 56 in fixed position upon the standard 50.

In order to provide means for gauging the height at which the sliders 56 and consequently the cutter 92 shall be set to most efficiently sever the top of any can, I prefer to provide a gauge 111 consisting of a substantially flat metal plate 112 having a pair of elongated apertures 113 which are adapted to receive the bolts 59 and 60 so that the plate 112 may be clamped between the nuts 114 and the slider 56 in a plurality of different positions. The plate 112 is provided with a forwardly projecting arm 111 which performs the function of a gauge.

The operation of my can opener is as follows:

The gauge 111 should preferably be set by means of the nuts 114 at such position that the cutter 92 will project below the gauge a sufficient distance to penetrate well into the top of the can 114. This adjustment is a permanent one and need not be changed until the cutter has been considerably worn down by resharpening or otherwise. The cutting mechanism should first be moved to its uppermost position by means of lifting the handle 102 to the linkage position shown in Fig. 4. The shoes 34 and 46 may be moved to their outermost position by rotating the crank 25 in a counter-clockwise direction, the sliders 18 and 41 progressing outward upon the left and right hand screws 22 and 23. A can may then be placed upon the base 10 and slid backward to the position shown in dotted lines at 116 in Fig. 2 underneath the gauge 111. By releasing the cam 109 by means of the bolt 110 the slider 56 bearing the entire cutting mechanism may be moved upward or downward and adjusted to such position that the gauge 111 rests upon the upper edge 117 of the cam and the slider 56 may be clamped in such position.

The can may then be placed between the jaws 34 and 46 and by rotating the crank 25 in a clockwise direction, the jaws will be actuated by the left and right-hand screws 22 and 23 toward each other to such distance as is necessary to clamp the base of the can between them, the serrated surfaces 39 serving to effectively prevent rotative movement of the can. It should be noted that the relative positions of the jaws 46 should be such that when any can is clamped between them the can is accurately centered beneath the point 84 in the axis of the shaft 73. For this pur-

pose it is sufficient that the surfaces 39 be located at equal distances from the axis of the shaft 73.

By pulling forward and downward on the lever 102 the mechanism can be brought into the position shown in Fig. 1, the point 84 penetrating the center of the top of the can and the cutter 92 penetrating the top of the can adjacent the outer wall of the same. The adjustment of the slider 56 and the cutting arm 87 having been once made, a plurality of cans of the same size may have their tops removed and by simply clamping the can upon the base, piercing its top as just described, and 15 rotating the crank 96 through a sufficient arc to cause the cutter to make one revolution. The sloping edge of the cutter 92 will then follow the inside of the wall of the can 115 severing the top therefrom while the point 20 84 will hold the top in proper position until the top is completely severed. The handle 102 may then be lifted, the can unclamped and removed, the cover removed from the point 84 and a second can put in place for 25 the same operation.

Referring to Fig. 5 I have here shown a modified form of linkage in which the bolts 59 and 106 are connected by a coil spring 118 thereby tensioning these parts toward each 30 other so that when the toggle formed by the links 101 and 104 is in the position shown the spring positively presses the link 104 against the leg 65, thereby providing a more positive means of locking the same. The spring also 35 performs an additional function when the linkage is in the dotted line position shown in Fig. 4 since it may be made of sufficient strength to support the mechanism in the upper position without physical effort. It 40 will thus be observed that I have invented a can opener which is capable of efficiently and expeditiously severing the tops of cans of many different sizes and which includes means for gauging the height of any can and 45 setting the cutting mechanism accordingly so that the cutter may be easily moved into and out of operating position without changing such adjustment.

While I have illustrated and described the 50 specific form of my invention, many changes may be made without departing from the spirit of the invention and I do not wish to be limited to the precise details of construction set forth but desire to avail myself of all 55 changes within the scope of the appended claims.

Having thus described my invention what I claim is new and desire to secure by Letters Patent of the United States is:

60 1. In a can opener, the combination of a supporting base having an upright standard, with means to retain a can in fixed position on said base, a frame adjustably mounted on said standard, a bearing movably mounted on said frame, a measuring stop on

said frame, and means for cutting out the top of a can mounted in said bearing.

2. In a can opener, the combination of a supporting base having an upright standard, with a slider mounted for sliding movement 70 on said standard, a lever pivotally supported on said slider, said lever having a bearing therein, a second lever pivoted on said slider, a toggle link connecting said levers, a shaft mounted in said bearing, means located axially of said shaft to pierce the top of a can, adjustable means mounted on said shaft for cutting out the top of a can, and means for actuating said shaft. 75

3. In a can opener, the combination of a supporting base having an upright standard, with a slider mounted for sliding movement on said standard, a lever pivotally supported on said slider, said lever having a bearing therein, a second lever pivoted on said slider, a toggle link connecting said levers, a shaft mounted in said bearing, means located axially of said shaft to pierce the top of a can, a radial arm adjustably carried by said shaft, 80 and a downwardly extending pointed cutter 85 leg carried by said arm. 90

4. In a can opener, the combination of a supporting base having an upright standard, a slider on said standard, means for cutting out the top of a can movably supported on said slider, a gauge for setting said slider at operative height for any size of can, and means for adjusting said gauge. 95

5. In a can opener, the combination of a frame having a base, with an upright standard having grooves in its edges, a slider on said standard comprising a pair of guides adapted to slide in said grooves, a lever pivotally mounted on said guides, said lever having a transverse bearing formed therein, a shaft mounted in said bearing, a cutter arm carried by said shaft, and means for rotating said shaft. 100

6. In a can opener, the combination of a frame having a base, with an upright standard having grooves in its edges, a slider on said standard comprising a pair of guides adapted to slide in said grooves, a lever pivotally mounted on said guides, said lever having a transverse bearing formed therein, a shaft mounted in said bearing, a cutter arm carried by said shaft, means for rotating said shaft comprising a bevel gear on said shaft, a second shaft at right angles to said first shaft, a bevel gear on said latter shaft and a crank. 110

7. In a can opener, the combination of a frame having a base, with an upright standard having grooves in its edges, a slider on said standard comprising a pair of guides adapted to slide in said grooves, a lever pivotally mounted on said guides, said lever having a transverse bearing formed therein, a shaft mounted in said bearing, a cutter arm carried by said shaft, means for rotating said shaft, a second lever pivoted to said slider, 115

said second lever having a handle and a connecting link between said levers.

8. In a can opener, the combination of a frame having a base, with an upright standard having grooves in its edges, a slider on said standard comprising a pair of guides adapted to slide in said grooves, a lever pivotally mounted on said guides, said lever having a transverse bearing formed therein, a shaft mounted in said bearing, a cutter arm carried by said shaft, means for rotating said shaft, a second lever pivoted to said slider, said second lever having a handle, and a spring connected between said levers to retain the same in either of its positions.

9. In a can opener, the combination of a frame having a base, with an upright standard having grooves in its edges, a slider on said standard comprising a pair of plates having opposed flanges adapted to slide in said grooves, a lever having its end spacing said plates, a bolt pivotally mounting said lever on said plates, a cutter revolvably mounted on said lever and means carried by said lever for actuating said cutter.

10. In a can opener, the combination of a frame having a base, with an upright standard having grooves in its edges, a slider on said standard comprising a pair of plates having opposed flanges adapted to slide in said grooves, a lever having its end spacing said plates, a bolt pivotally mounting said lever on said plates, a cutter revolvably mounted on said lever, means carried by said lever for actuating said cutter, a second lever having a link connected to said first mentioned lever and a bolt for pivoting said second lever to said plates.

11. In a can opener, the combination of a frame having a base, with an upright standard having grooves in its edges, a slider on said standard comprising a pair of plates having opposed flanges adapted to slide in said grooves, a lever having its end spacing said plates, a bolt pivotally mounting said lever on said plates, a cutter revolvably mounted on said lever, means carried by said lever for actuating said cutter, a second lever having a link connected to said first mentioned lever, a bolt for pivoting said second lever to said plates, and a cam mounted on said bolt to fix the position of said slider.

12. In a can opener, the combination of a frame having a base, with an upright standard having grooves in its edges, a slider on said standard comprising a pair of plates having opposed flanges adapted to slide in

said grooves, a lever having its end spacing said plates, a cutter revolvably mounted on said lever, means carried by said lever for actuating said cutter, a second lever having a link connected to said first mentioned lever, a bolt for pivoting said second lever to said plates, a cam mounted on said bolt to fix the position of said slider, and a gauge adjustably carried by said bolts.

13. In a can opener, the combination of a frame having a base with an upright standard having grooves in its edges, a slider comprising a pair of plates having inwardly turned flanges in said grooves, a lever adapted to space said plates, a bolt pivoting said lever to said plates, said lever having a transverse bearing, a goose neck and a second bearing at right angles to said transverse bearing, a shaft in each of said bearings, a cutter carried by the shaft in said transverse bearing, bevel gears on said shafts and a crank carried by one of said shafts.

14. In a can opener, the combination of a frame having a base with an upright standard having grooves in its edges, a slider comprising a pair of plates having inwardly turned flanges in said grooves, a lever adapted to space said plates, a bolt pivoting said lever to said plates, said lever having a transverse bearing, a goose neck and a second bearing at right angles to said transverse bearing, a shaft in each of said bearings, a cutter carried by the shaft in said transverse bearings, bevel gears on said shafts, a crank carried by one of said shafts, a second lever pivotally mounted on said slider, and a link connecting said levers.

15. In a can opener, the combination of a frame having a base with an upright standard having grooves in its edges, a slider comprising a pair of plates having inwardly turned flanges in said grooves, a lever adapted to space said plates, a bolt pivoting said lever to said plates, said lever having a transverse bearing, a goose neck and a second bearing at right angles to said transverse bearing, a shaft in each of said bearings, a cutter carried by the shaft in said transverse bearings, bevel gears on said shafts, a crank carried by one of said shafts, a second lever pivotally mounted on said slider, a link connecting said levers, and a spring for holding said levers in either of two positions.

In witness whereof, I hereunto subscribe my name this 19th day of January, 1927.

ANDREW RYCKMAN.
